UNITED STATES PATENT OFFICE

2,049,263

STRUCTURAL ELEMENT

Jonathan Jones, Bethlehem, Pa., assignor to
McClintic-Marshall Corporation, a corporation
of Pennsylvania

Application March 25, 1933, Serial No. 662,741

7 Claims. (Cl. 189—37)

This invention relates to structural elements, especially to a type of knock-down plate girder or beam designed for use where room for assembly is limited and where the pieces to be handled in 5 making up the girder or beam must be relatively compact and light.

Frequently, where knock-down plate girders are used, it is desirable to progress by removing rear portions from such a girder and rebuilding these 10 same portions on in front in a repetitive series of moves. It is a particular object of my invention to provide a knock-down plate girder in which the parts that make up the girder are interchangeable end-for-end, and this in such a manner 15 that assembly and disassembly of the girder may be accomplished with a minimum of effort and of required space.

Heretofore knock-down plate girders have been used wherein in the assembled girder the continuity of the web plate was discontinued at various places and no means were provided whereby the shear value of the web plate at such places was restored. This construction resulted in a serious defect, in that the web plate, and therefore 25 the girder as a whole, was not of equal shear strength throughout its length and could easily be crippled by some fortuitous arrangement of loading and supports which would be perfectly natural to the user, but critical as to the web 30 action. It is another object of my invention to provide a knock-down plate girder in which the value of the web plate for resisting shear is partially or wholly (as may be elected) restored at all points where the continuity of the web plate is 35 interrupted by reason of its knock-down requirements.

In a like manner the angles used to reinforce the web plate heretofore have been used without restoring the shear value at the points of interrupted continuity. It is another object of my invention to provide means whereby the shear value of the reinforcing angles at the points of interruption is partially or wholly (as may be elected) restored.

It is another object of my invention to meet the improved conditions and objects stated above by means of novel features which will be more fully understood from the following description and claims taken with the drawings in which:

Fig. 1 is a front elevation of a girder constructed in accordance with my invention;

Fig. 2 is a transverse section taken along the line 2—2 of Fig. 1;

Fig. 3 is a transverse section taken along the line 3—3 of Fig. 1;

Fig. 4 is a transverse section taken along the line 4—4 of Fig. 1;

Fig. 5 is an enlarged fragmentary section taken along the line 5—5 of Fig. 1;

Fig. 6 is an enlarged fragmentary section of a

modification to the embodiment of my invention as shown in Figs. 1 and 5;

Fig. 7 is a front elevation of another modification to the embodiment shown in Fig. 1; and

Fig. 8 is a transverse section taken along the line 8—8 of Fig. 7.

As illustrated in the accompanying drawings the numeral 10 designates a knock-down plate girder embodying a preferred form of my invention provided with a series of web plates 11 placed 10 in overlapping relation at their ends, as at 12 and 13. The web plates 11 are demountably united at the laps by demountable fastening devices 14. Along the outer edge of each web plate and on that side whereon the next adjacent web plates 15 (or plate if at girder end) overlap are filler plates 15. The filler plates 15 are made the same thickness as the web plates with the result that, with the filler plates 15 in place, the assembled web plates along their edges on both sides are flush 20 from one end to the other. An appreciable gap or clearance is preferably left between the ends of the filler plates 15 and the ends of the adjacent web plates 11, as at 16. This gap or clearance makes for a saving of cost in manufacture and 25 for subsequent ease in assembly and disassembly. As a further convenience in assembly and disassembly the filler plates 15 may be tack welded in place on the web plates 11, though this is not a necessity. It should also be noted that the filler 30 plates 15 by reason of the overlapping arrangement of the web plates 11 occur alternately on opposite sides of the girder on each successive web plate. Along each outer edge and on the opposite sides thereof of the assembled web plates 35 11 and the filler plates 15 are a series of reinforcing angles 17. The angles 17 are placed end to end in length preferably twice that of the center distance between successive web plates, which permits preferably of arranging the meeting ends of the angles 17 so as to always occur 40 midway of the ends of a web plate 11 as at 18 and preferably always on the same side with the filler plates 15 for that particular web plate. As indicated at 18 an appreciable gap or clearance 45 is preferably allowed between the ends of angles 17 for ease of manufacture and subsequent ease of assembly and disassembly. Splice bars 19 are placed to overlap the vertical outside faces of the adjacent ends of the angles 17. Suitable demountable fastening devices 20, 21, and 22 secure 50 the angles 17, splice bars 19, and filler plates 15 to the assembled web plates 11 and make there-with a temporary integral unit.

It will be realized that the spacing of the various fastening devices 14, 20, 21, and 22 and the necessary adaptation therefor of the associated parts 11, 15, 17, and 19 will be standardized so that the said associated parts will be interchangeable one with another in their appointed places. 60

In Fig. 6 I show a modification of my above described invention in which the splice bar 19' has an outstanding leg in contact with the adjacent outstanding legs of the angles 17', and is demountably attached thereto by means of suitable fastening devices 23.

It will be seen from the above description that I have provided a knock-down plate girder which is particularly adapted for use in cramped areas where it is desired to advance the work for which the girder is being used by removing the demountable parts from the rear part of the girder and rebuilding the same parts to the front part of the girder in a repetitive series of moves. However, there may be occasions where this repetitive rebuilding feature is not necessary, and where, although the structure of the girder is of a temporary nature, its use is more or less permanent. In this case it may be desirable to have a finished end to the girder such as I show as a modification in Figs. 7 and 8. Here, at the end of the girder 18', I replace the standard reinforcing angles 17 with special angles 24 and 25 which are cut off flush with the exposed end of the end web plate 11. Also I supply a filler plate 26 which takes the place of what would normally be the lapped-over end of the next adjacent web plate. The filler plate 26 and the ends of the special angles 24 and 25 are demountably united with the web plate 11 by means of the demountable fastening devices 14 and 21 hereinbefore described.

From the foregoing description it will be seen that I have devised a knock-down web plate girder of approximately uniform resistance to shear throughout its length. This I secure by overlapping the adjoining ends of multiple web-plates and by splicing successive reinforcing angles by means of filler plates and splice bars in such a manner that I restore to the assembled girder partially or wholly (as may be elected) the shear value that would otherwise be lost due to the break in the continuity of the web plates and the reinforcing angles. At the same time I have devised a knock-down web plate girder which is simple and compact of design, economical in cost of manufacture, and adapted to be conveniently manipulated in difficult places of assembly and disassembly.

While I have shown my invention in certain preferred forms, it will be obvious to those skilled in the art that is is not so limited, but is susceptible of various other changes and modifications without departing from the spirit thereof, and I desire, therefore, that only such limitations shall be placed thereupon as are imposed by the prior art or as are specifically set forth in the appended claims.

Having thus described what I claim as new and desire to secure by Letters Patent is:

1. A structural element comprising a series of plate members joined in an end-to-end overlapping relation, the lapped plates being arranged alternately in two parallel planes, fastening means at the lapped joints, filler plates along the longitudinal edges of each plate and in the same plane as the next adjacent plate, a series of chord members in an end-to-end relation along the longitudinal edges of the plate members, splice members disposed in overlapping relation with the ends of the chord members, and means joining the chord members, the filler plates, the splice members, and the plate members.

2. A structural element comprising a series of

plate members arranged in overlapping relation, the plates being arranged alternately in two parallel planes, fastening means at the lapped joints, filler plates along the longitudinal edges of each plate and in the same plane as the next adjacent plate, a series of chord members in an end-to-end relation along the longitudinal edges of the plate members, said chord members having a length approximately twice that of the plate members and so arranged that the end-to-end relation occurs at and on the filler plate side of a plate member, splice members disposed in an overlapping relation with the ends of the chord members, and means joining the chord members, the filler plates, the splice members, and the plate members.

3. A structural element comprising a series of plate members arranged in overlapping relation, the plates being arranged alternately in two parallel planes, fastening means at the lapped joints, filler plates along the longitudinal edges of each plate and in the same plane as the next adjacent plate, a series of chord members in an end-to-end relation along the longitudinal edges of the plate members, said chord members having a length such that the end-to-end relation occurs at and on the filler plate side of a plate member, splice members in an overlapping relation with the ends of the chord members, and means joining the chord members, the filler plates, the splice members, and the plate members.

4. A structural element comprising a series of plate members joined in an overlapping relation, the lapped plates being arranged alternately in two parallel planes, fastening means at the lapped joints, filler plates tack welded in place along the longitudinal edges of each plate and disposed in the same plane as the next adjacent plate, a series of chord members in an end-to-end relation along the longitudinal edges of the plate members, splice members disposed in an overlapping relation with the ends of the chord members, and means securing the chord members, the splice members, the plate members, and the filler plate members together.

5. A structural element comprising a series of plate members joined in an overlapping relation, the lapped plates being arranged alternately in two parallel planes, fastening means at the lapped joints, filler plates along the longitudinal edges of each plate and in the same plane as the next adjacent plate, a series of chord angle members in an end-to-end relation along the longitudinal edges of the plate members, splice angle members disposed in an overlapping relation with the ends of the chord angle members, means joining the chord angle members, the splice angle members, and the filler plates to the plate members, and means joining the splice angle members to the chord angle members.

6. A structural element comprising a plurality of web plates having ends in overlapping relation, means securing the adjacent ends of said plates, chord members secured to the web plates, and filler members intermediate the web plates and the chord members.

7. A structural element comprising a plurality of web plates having ends in overlapping relation, means securing the adjacent ends of said plates, chord members secured to the web plates, filler members intermediate the web plates and the chord members, and means joining said chord members.

JONATHAN JONES.
